FEED STOP

Richard Lester Wilcox, Waterbury, Conn., assignor to The Waterbury Farrel Foundry and Machine Company, Waterbury, Conn., a corporation of Connecticut

Application January 5, 1942, Serial No. 425,670

10 Claims. (Cl. 10—11)

This invention relates to new and useful improvements in feed stops.

A principal object of the invention is to provide a feed stop of simple design and construction that may be moved into and out of its operative position as a unit and whereby full access to the tools is given the operator when the feed stop is in its non-operative position.

Other objects of the invention will be apparent from the following description and the accompanying drawing.

To these ends, the invention consists in the feed stop, having certain details of construction and combinations of parts, as will be hereinafter described and more particularly pointed out in the claims.

Referring to the drawing, wherein like numerals of reference indicate like parts in the several figures:

Figure 1 is a view of this improved feed stop shown as associated with other machine parts;

Figure 2 is an elevation thereof, the parts in section being taken generally upon line 2—2 of Figure 1;

Figure 3 is a front elevation thereof;

Figure 4 is a fragmentary view of a portion of the feed stop illustrating an alternative length stop plug; and

Figure 5 is an enlarged front elevation of the stop plug.

The feed stop is shown and described herein as being applied to an upsetting or heading machine, wherein a wire length is intermittently advanced to a stop, and the projecting portion cut therefrom forming a workpiece for subsequent operations. The length of the workpiece is thus determined by the position of the stop. Therefore, it is desirable that the stop should be adjustable to permit the production of workpieces of different lengths with the minimum inconvenience, and secured in its adjusted positions against accidental displacement. The feed stop, being in front of the operating tools, is to that extent an obstruction when access is desirable for positioning, adjusting and replacing machine parts or tools. One form of conventional feed stop is movable a limited distance about an axis substantially parallel with the wire as fed through the machine. While such stop provides for a larger working space than a non-movable stop, nevertheless it is only partially advantageous, because of its very limited range. Other objections arise from its structure and assembly, one such objection being the fact that it is upon a member rotatably mounted in the machine with

its axis substantially parallel with that of the wire feed. This mounting is both difficult and costly to machine and assemble.

These and other objections to a feed stop of this general character are obviated in the feed stop shown and described, wherein the stop element is upon a supporting structure above the feed line and during operation of the machine held in a fixed position, is adjustable for various lengths of workpieces, and mounted so as to swing as a unit out of its fixed position in the space between the operating tools, thus leaving the same free and open.

In a header or upsetting machine a gate or ram (not shown) carrying one or more punches is movable toward and away from the die block, wherein one or more dies are fixed. The punches and dies function to fabricate a workpiece therebetween. By reason of the relative position of the gate or ram and the die block, the space therebetween is limited for the operator to install, take down or adjust the tools.

In the drawing, the numeral 10 designates the frame of a machine; 11 a die block mounted therein; 12 a backing plate between the frame and die block, and upon the upper face of which are the lugs 13. Between these lugs, upon a pintle 14 is the lug 35 of the feed stop base 15, which is separably secured to the die block by a screw 18, having a nut 19 thereon, which passes through opening 20 therein. Upon the base 15 is a stop arm 21 which is slidably adjusted thereon by a screw 22 threaded therein, and secured in its adjusted positions by a bolt 23 with a nut 24 thereon, which passes through the slot 16. The head of this bolt projects into a recess 17 and is held thereby against rotation. The screw 22 is rotatable in the lug 34 and held against endwise movement by a nut fixed on the screw by the pin 36. The lower portion 25 of the stop arm is relatively narrow and has an angular face 26 opposite the die block 11. In the bottom of this stop arm is a removable stop plug 27, preferably of hardened material. The lugs 13 are shown herein as being on the backing plate, but they may be placed on the die block, or the frame, or other part, as may be desired.

In the several figures the feed stop is shown by full lines in its operative position. When so positioned, the stop arm 21 is opposite the face of the die block 11, and the head 28 of the stop plug 27 opposite the opening 29 in the cut-off die 30. The successive outer ends of the wire length 31 abut against the head 28 as the wire length is successively advanced by the feed mechanism,

and thus limits its advance movement. That portion of the wire length projecting into the open space beyond the face of the die 30 is cut off by a conventional cut-off mechanism (not shown). The length of the projecting portion of the wire is determined by the position of the stop arm 21 relative to the die 30. One of such adjusted positions is shown by broken lines in Figure 2. This feed as a unit is moved out of its operative position, as shown in Figure 2 by first removing the nut 19 and then swinging it upon the pintle 14 to its non-operative position illustrated by broken lines in Figure 2, a part thereof resting on a stop pin 32, or other part. When in this latter position the space in front of the die block 11 is open, unobstructed and accessible to the operator for such work as is needful to be done therein.

In Figure 4 there is illustrated a stop plug 27, with a head 28 of greater height than that shown in Figure 2. This stop plug is advantageous for workpieces of very short length, as the face of the head can be brought closer to the die 30. The top face of the head 28 may be flattened as at 33 to engage a shoulder on the stop arm 21 (Figs. 2, 4 and 5) to hold the same against rotation.

Within the scope of the claims various changes and alterations may be made in the design and construction of this improved feed stop without departing from the spirit thereof.

What is claimed is:

1. In combination with a die block through which material is fed; a backing plate having lugs thereon at a point above and in rear of the face of the die block; a base plate hinged to the lugs; a stop arm thereon which is opposite the face of the die block when the stop means is in its operative position; and a stop plug in the stop arm in the path of the material.

2. Stop mechanism of the character described having a hinged base member, a stop arm movably mounted thereon and projecting below the base member; mechanism having means to adjustably hold said stop arm against endwise movement having an intermeshing engagement with the stop arm for moving the same into its various positions, the stop arm having one angular wall below the base member and of less width at the bottom thereof than near the base member.

3. Stop mechanism of the character described having a hinged base member, a stop arm movably mounted thereon and projecting below the base member; mechanism, as a screw, held against movement having a threaded engagement with the stop arm for moving the same into its various adjusted positions, the stop arm having one angular wall below the base member and of less width below the base member; and a stop lug in the stop arm having a head exposed upon one side of the arm.

4. The combination with a die block or the like, through which material is fed, of stop means for limiting the travel of the material, the stop means when in its feed limiting position being fixed with respect to the die block, and comprising in part a member hinged above the die block and projecting beyond the face of the die block, and an arm on the member positioned in front of the face of the die block when the stop means is in its feed limiting position, and releasable means for securing the stop means with the arm in its feed limiting position, the mounting of the stop means being such that it may be moved out of the space in front of the die block and into a position thereabove.

5. In combination with a die block or the like, through which material is fed, a member having one or more lugs above the plane of the material as it moves through the die block, a base member hinged to the lugs and overhanging the face of the die block, a stop member upon the base member that projects therefrom in front of the face of the die block and in the path of the material, means for moving the stop member toward and away from the die block with respect to the base member, and releasable means for securing the base member and whereby the stop member may be moved out of the space in front of the die block and into a position thereabove.

15 6. In combination with a die block or the like, through which material is fed, a member having one or more lugs above the plane of the material as it moves through the die block, a base member hinged to the lugs and overhanging the face of the die block, and in one position fixed with respect to the die block, a stop member slidably upon the base member and projecting therefrom in front of the face of the die block in the path of the material, and securing means to hold the stop member against movement on the base member.

25 7. In combination with a die block or the like, through which material is fed, a backing plate in rear of the die block, a base plate hinged to the backing plate and in one of its positions overhanging the face of the die block, means for securing the base plate in the last mentioned position, and a stop arm depending from the base plate opposite the die block when in a position to limit the movement of material through the die block, the connection between the base plate and backing plate being such that when the securing means is released the base plate with the stop arm thereon may be moved, carrying the stop arm from its feed limiting position to a position above 30 and in rear of the face of the die block.

8. In combination with a die block or the like, a support member above and in part overhanging the die block, stop means on the support member opposite the face of the die block for limiting the extent of movement of material beyond the face of the die block when the support member is in a fixed position, and means for mounting the support member whereby it may be moved upon its mounting and carry the stop means out of the space in front of the die block and above and in rear of the face of the die block.

35 9. In combination with a die block or the like, a support member above and in part overhanging the die block, stop means having a sliding engagement with the overhanging portion of the support member and opposite the face of the die block for limiting the extent of movement of material beyond the die face when the support member is in a fixed position, and means for mounting the support whereby it may be moved upon its mounting and carry the stop means out of the path of movement of the material and above and in rear of the face of the die block.

40 10. In combination with a die block through which material is fed, a backing plate having lugs thereon at a point above and in rear of the face of the die block; a base plate hinged to the lugs; a stop arm on the base plate which is opposite the face of the die block when the stop arm is in its operative fixed position; and releasable means for securing the base plate and whereby the stop arm may be moved out of the space in front of the die block and into a position thereabove.

RICHARD LESTER WILCOX.
